[57] CLAIM

The ornamental design for a rope coiling and storing
mechanism, as shown and described.

DESCRIPTION

FIG. 1 is a perspective view of a rope coiling and storing
mechanism showing my new design;

FIG. 2 is a front elevational view thereof;

FIG. 3 is a left side elevational view with the opposite
side being a mirror image thereof;

FIG. 4 is a top plan view thereof;

FIG. 5 is a bottom plan view thereof; and

FIG. 6 is a rear elevational view thereof.
